UNITED STATES PATENT OFFICE

ROBERT BREYER, OF MILWAUKEE, WISCONSIN

STOCKING-ANKLE-MACHINE ATTACHMENT

Application filed January 24, 1927. Serial No. 163,295.

The invention relates in general to a straight bar knitting machine for knitting so-called full-fashioned stockings and the invention specifically relates to an attachment 5 for such machine for knitting into the ankle portion of the flat stocking blank a V-shaped design more particularly described in my co-pending application Serial No. 163,294 filed under even date and entitled "Stocking design and method of knitting the same."

In the said application there is disclosed a form of high splice above the usual reinforced heel which is characterized by stripes knit into the fabric of the stocking on opposite 15 sides adjacent the selvedge edges and arranged so that when the stocking is sewed up the back seam the stripes form in effect an inverted V-shape design to provide a means for visually slenderizing the ankle and to provide 20 an ornamental configuration above the low shoe of the wearer.

The primary object of the invention is to provide a simple form of machine, or rather a simple form of attachment to a conventional 25 form of straight bar stocking knitting machine, for mechanically controlling the feeding of yarn or thread to the needles of the machine in such way as will produce the desired form of ornamental design in the stocking 30 as an incident of the usual knitting operation.

More specifically, an object of the invention is to provide a simple form of control for two of the usual thread carrier bars in order 35 to produce thin stripes extending at an angle to both the courses and to the wales of the knitting in order to produce the desired design.

Among the other objects of the invention 40 is to provide a thread carrier control which can be quickly brought into operation at the desired point in the progress of the knitting of the stocking; to provide a simple form of adjustment by means of which the width of the desired stripes may be readily set and quickly changed at will to some other required width; to provide as part of the control means for varying the angularity of one or more of the stripes and in which when once 45 set the required stripe or stripes may be knit 50

into the fabric automatically and without necessity of further attention on the part of the operator until the desired length of stripe has been knitted.

Various other objects and advantages of the invention will be in part obvious from an inspection of the accompanying drawings and in part will be more fully set forth in the following particular description of one form of device embodying the invention, and the invention also consists in certain new and novel features of construction and combination of parts hereinafter set forth and claimed.

In the accompanying drawings,

Fig. 1 is a view largely diagrammatic showing certain parts of a conventional form 65 of straight bar knitting machine equipped with a preferred embodiment of my invention and shown in position at the termination of the stripe knitting operation; and

Fig. 2 is an enlarged view in side elevation of either one of the stripe width defining stops shown in plan in Fig. 1.

In the drawings, there is shown three of the usual thread carrier bars 10, 11, 12, forming 70 part of a straight bar knitting machine of the type now in general use in knitting full fashioned stockings and in which there are usually a much larger number of such bars. It is understood that these bars are controlled at one end by means of a jacquard or other pattern controlling device for regulating the throw of the bars and for timing the action of these bars in knitting the different parts of the stocking, as is well known 75 in knitting machines of the type under discussion.

One such bar 12 is provided with a thread carrier 13, in this case being the thread carrier to supply the needles 14 with thread to knit the stocking from one selvedge edge 15 to the other edge 16 and this bar 12 and its associated carrier 13 may be regarded as representative of the other similar bars and carriers used in knitting the different parts of 80 the stocking.

Bars 10 and 11 are provided respectively 85 with a left design thread or yarn carrier 17 and a right design thread or yarn carrier 18 but it is understood that these yarn carriers 90

are designed normally to knit other parts of the stocking blank. From the showing in Fig. 1 it is to be understood that the carrier 17 supplies thread to the needles used to knit the left stripe 19 and similarly the carrier 18 supplies thread to the needles which knit the right stripe 20. All of the bars are reciprocated through the actuation of the usual bar throwing mechanism and are limited in their movement in both directions by means of adjustable stops 42 forming conventional parts of stocking knitting machines now in general use and are not to be confused with the special stripe controlling stops featured in this disclosure, shown at 21 in Fig. 1 and more definitely disclosed in Fig. 2. The present disclosure features the use of a pair of supplemental stops or rather stripe width-defining controls 21, one for each of the rods 10 and 11 which in turn control the reciprocating yarn or thread carriers 17 and 18.

As the construction is the same for the controls of both bars the detailed description of either one will be sufficient for the other. The controls are formed of angle plates 22; a vertically upstanding flange 23 of which is fastened to the forward side of its associated bar by means of rivets 24. The upper flange 25 extends across the top of the bar as shown particularly in Fig. 1 and is provided with two longitudinally spaced apart upstanding fingers 26 and 27. These fingers may include horizontally extending set or stop screws 28 and 29 designed to be adjusted to provide a variable space 30 therebetween. A relatively fixed stop or abutment 31 carried at the forward end of a carriage 32 is designed to be projected into the space 30 as particularly shown in Fig. 2. The two carriages 32 are slidably mounted upon one of the longitudinal bars 33 forming one of the parts of the conventional form of knitting machine. The abutment 31 is in the form of a rectangular bar and is slidably mounted in its associated carriage for vertically adjusted movement so that it may be lowered at will into position between the opposing ends of the set screws 28 and 29 as shown in Fig. 2, or may be elevated so that the bar and the attachment plate 22 may be free to reciprocate beneath the elevated abutment bar 31. Bar 31 may be secured in either its elevated or in its lowered operative position by means of a conventional form of a binding screw 34.

It is the intent to cause the relatively fixed abutments 31 to gradually approach each other as the knitting of the stocking progresses course after course towards its toe end and thus cause the stripes to approach each other as shown in the stocking blank 35, Fig. 1. For the purpose of causing the thread carriers 17 and 18 forming the stripes 19 and 20 to approach each other, the carriages 32 carrying the abutments engage a right and

left hand feed screw 36 and which feed screw is in turn advanced by some conventional form of feed ratchet 37 coupled to work in synchronism with the other parts of the knitting operation. In the instant case the parts are so timed that five courses indicated by parallel lines in block or set 38 are knit in each stripe before the ratchet 37 advances the feed screw so as to displace the stops 22 a short distance inwardly from its previous position to form the next succeeding block 39 of five courses.

It will be understood that the stops 22 are advanced towards each other and in the direction parallel to the reciprocating bars with a step-by-step movement. It is obviously within the scope of the disclosure to have the lead screw 36 geared directly to any power shaft of the machine conventionally and thus continuously rotating and in which case of course the staggered or step appearance of the opposite side edges 30 and 41 of the stripes 19 and 20 will be defined by a more or less straight line.

When the desired length of stripe has been knitted into the fabric the abutments 31 are withdrawn from their operative positions, or the bars 10 and 11 are otherwise rendered inoperative and the conventional knitting of the balance of the stocking is continued even using the bars 11 and 12. Should it be desired to utilize the carriers 17 and 18 for the purpose of knitting into the fabric the usual form of high splice, as shown in the companion application, the feed screw 36 may be held from rotating and the outer stop screw 28 of each bar may be adjusted so that the carriers may feed the needles up to or almost up to the selvedge edges 15 or 16 as the case may be and thus form the square high splice illustrated in the drawing in the companion application previously referred to.

By means of a device of the character herein disclosed it is possible at small cost to install an attachment to the conventional form of full-fashioned stocking knitting machine and to add the stripe during the knitting of the stocking and without in any way modifying conventional parts or interfering with the normal and usual operation of these parts. The usual end stops for controlling the bars are retained and the attachment is brought into operation only when it is desired to be used. As any number of stops 21 with varying distances between their fingers 26 and 27 may be positioned along the length of each of the bars 11 and 12, it is possible to obtain various prescribed widths to the inclined stripes even without necessity of using the adjusting screws 28, 29.

Having thus described my invention, I claim:

1. In a straight bar knitting machine, the combination of means complete for knitting a full fashioned stocking and including a

plurality of reciprocating bars, each provided with the usual stops and equipped with a thread carrier adapted for knitting a stocking part from one to the other of its selvedge edges, mechanism for knitting a design into the stocking, said mechanism including two of said bars, one for forming the part of the completed design adjacent one of the selvedge edges and the other for forming the part thereof adjacent the other edge, a control for each of said two bars distinct from the usual stops for limiting the throw of said bars when knitting conventionally from one to the other selvedge edge, each control including a pair of stops carried by its associated bar and provided with means adapted to be fixedly spaced apart for defining the length of reciprocatory movement of its associated bar and thus defining the width in each course of the design part, a pair of relatively fixed abutments one for each control adapted to be positioned between its associated spacing means when it is desired to use said bars for feeding yarn in knitting the design into the blank, and a single step-by-step means for progressively shifting said abutments towards each other thus causing said two controls progressively to move towards each other, each away from its contiguous selvedge edge and thus progressively and uniformly shift the controls as the knitting progresses and thus shift the location of the design parts during the progress of the knitting of the stocking blank.

2. A straight bar knitting machine including mechanism for knitting a design into the stocking and including a reciprocating bar provided with a thread carrier adapted normally to feed thread to the needles for knitting a structural part of the stocking blank, an attachment for said machine for knitting a design into the stocking blank, said attachment comprising a control for said bar, additional to the usual control for regulating the throw of such bars during the conventional knitting of the blank, said additional control including a pair of fingers fixedly spaced apart on said bar for defining the length of reciprocatory movement of the same and thus defining the width in each course of the design part, and means for causing said control to have bodily movement in a direction parallel to that of the reciprocating bar thereby to change the relative position in succeeding groups of courses of the portions of the design in said groups.

3. In a machine for knitting full-fashioned stockings, the combination of a thread carrier bar mounted for reciprocatory movement, a pair of stop fingers carried by the bar, set screws carried by the fingers and providing a variable gap distance therebetween, a single abutment projecting into the gap between the pair of screws and engaged by the screws to limit the stroke of the bar in

each direction and means engaging said single abutment for advancing the same lengthwise of the bar.

4. The combination with a full-fashioned stocking knitting machine comprising complete mechanism for knitting a stocking blank and including a reciprocating yarn carrier for supplying yarn during the conventional knitting of parts of the stocking blank, of an attachment for the machine for knitting a design in the blank, said attachment including a control having a pair of spaced apart fingers, means for securing the control to the yarn carrier, a carriage slidable parallel to the direction of reciprocatory movement of said carrier, a stop movable with the carriage, disposed between the fingers and constituting an abutment for the fingers as they are reciprocated with the carrier, a feed screw for advancing the carriage and a feed ratchet adapted to be operatively connected to the knitting mechanism of the machine for rotating the feed screw.

5. In a full-fashioned stocking knitting machine, the combination of two thread carrier bars each provided with a control longitudinally offset from each other and each including means forming a gap extending lengthwise of its associated bar, a carriage supporting bar, and a feed screw including a left hand and a right hand screw part, two carriages slidably mounted on the carriage supporting bar, one operatively connected to be advanced by the right hand screw part and having a part disposed in one of said gaps and the other operatively connected to be advanced by the left hand screw part and having a part disposed in the other gap, said carriage parts disposed in the gaps in each instance constituting an abutment for limiting the longitudinal movements of its associated bar and shiftable into position out of the path of the control in the associated bar.

6. In a full-fashioned stocking knitting machine, the combination of a thread carrying bar, a carriage supporting bar and a feed screw, said bars and screw being disposed parallel to each other, said thread carrying bar provided with means forming a gap of fixed length, a carriage slidably mounted on the carriage supporting bar and operatively connected to said screw to be advanced in one direction thereby, and said carriage provided with an abutment adapted to be positioned in the gap for limiting the longitudinal movement of the thread carrying bar.

7. In a full-fashioned stocking knitting machine, the combination of a thread carrying bar, a feed screw, said thread carrying bar provided with means forming a gap of prefixed length, a carriage slidably mounted and operatively connected to said screw to be advanced in one direction thereby, and said carriage provided with an abutment adapted to be positioned in the gap for lim-

iting the longitudinal movement of the thread carrying bar, said abutment mounted to be moved into two positions, one positioned in the gap and the other in an out of the way position to permit the thread carrying bar to move independent of the carriage and means for securing the abutment in both of said positions.

Signed at Milwaukee, in the county of Milwaukee, and State of Wisconsin, this 14th day of January, A. D. 1927.

ROBERT BREYER.
